COMBINED AIR COMPRESSOR AND MOTOR.

1,105,494.

Specification of Letters Patent. Patented July 28, 1914.

Application filed June 6, 1913. Serial No. 772,079.

To all whom it may concern:

Be it known that we, DAVID E. CROUSE and CHARLES G. EIDSON, citizens of the United States, and residents of Annapolis, 5 in the county of Anne Arundel and State of Maryland, and THOMAS DAVIS, a citizen of the United States, and a resident of Wilkinsburg, in the county of Allegheny and State of Pennsylvania, have made certain 10 new and useful Improvements in Combined Air Compressors and Motors, of which the following is a specification.

Our invention relates to improvements in combined air compressors and motors, 15 and it consists in the combinations, constructions, and arrangements herein described and claimed.

An object of our invention is to provide a device which may be used either as a means 20 for compressing air or as a motor.

It is particularly adapted for use as a starting device for automobiles, and also as a means for compressing air for driving the starting device.

25 A further object of our invention is to provide a device of the nature described having valves which are brought into play when the device is used as a motor, but which are put out of operation when the 30 device is used as a compressor, thereby rendering the life of the valve mechanism of greater duration than it would otherwise be.

A further object of our invention is to provide a device having a novel form of 35 valve mechanism for accomplishing the above named objects.

Other objects and advantages will appear in the following specification and the novel 40 features of the invention will be particularly pointed out in the appended claims.

Our invention is illustrated in the accompanying drawings forming part of this application in which—

Figure 1 is a plan view of the device, 45 Fig. 2 is a vertical section through the device showing the valves in their normal position when the device is used as a compressor, Fig. 3 is a face view of one of the cams, Fig. 4 is a fragmentary section along 50 the line 4—4 of Fig. 1, Fig. 5 is a view similar to Fig. 2 showing the valves in one of the positions which they assume when the device is being used as a motor, Fig. 6 is a detail view of one of the check valves,

and Fig. 7 is a plan view of the valve shown 55 in Fig. 6.

In carrying out our invention we provide a base 1 upon which is mounted a casing 2 (see Fig. 1) having a plurality of cylinders such as those shown at A, B, C and D. 60 Each of the cylinders is provided with a piston as A', B', C' and D'. Secured to the upper part of the casing 2 is a valve casing 3, which extends above the cylinders. At one end of the valve casing is a cylindrical chamber 4, while at the other is a similar chamber 4'. The chamber 4 has a reduced extension 5, a similar extension 5' being provided for the chamber 4'. A partition 6 separates the chambers 5 and 70 5' and this partition has a central opening 6a. Within the valve chamber 4 is a piston valve 7 which is secured to a valve stem 8. At one end of the valve stem 8 is an auxiliary piston valve 9 which is disposed in 75 the extension 5 of the chamber 4. Between the partition 6 and the auxiliary piston valve 9 is a spiral spring 10. Disposed within the chamber 4 is a hollow cylinder 11. One end of the cylinder is closed by 80 a head 12 having an integral nut 13 which is screwed on an extension 14 of the stem or rod 8. A passage 15 extends from the end of the extension which is within the cylinder 11 and terminates at an opening 16 85 in the stem or rod 8.

The cylinder 11 is provided with an extension 11a which is arranged to slide through the end of the valve casing 3. A piston 17 is disposed within the cylinder 11 90 and is provided with a stem or rod 18 which extends through the portion 11a and is arranged to be engaged by the arm 19 of a bell-crank lever which is pivoted at 20, and which is provided with a depending arm 21, 95 which has a pivotal connection at 22 to the bell-crank lever. The arm 21 is arranged to be engaged by a cam 23 on the crank shaft 24. On the other side of the partition 6 are the piston valves 7' and 9', 100 the cylinder 11', the piston 17' and the other coöperating parts which are precisely similar to those already described. Each cylinder is provided with an air inlet such as that shown at a, b, c and d, which is controlled by a valve like that shown in Figs. 6 and 7. This valve has a body portion v having radially extending lugs v'. The

body portion is recessed as shown at v^2 and a spring s is disposed in this recess and is arranged to engage a bearing plate p which caps the cylinders. An opening p' is provided in the bearing plate. The spring v^2 keeps the valve normally in the position shown in Fig. 6, but when the air is exhausted within one of the cylinders A, B, C or D, the excess pressure of the atmosphere will push the valve downwardly and pass around between the lugs v' and through the ports p' into the cylinder. The valve prevents any escape of the air from the cylinder through the inlet ports p' and a . Arranged to establish communication between each of the cylinders and the interior of the valve casing 3 are ports a' , a^2 , b' , b^2 , c' , c^2 and d' , d^2 . Intake ports 25, 25 x and 25 y are provided in the valve casing.

In the rear of the valve casing 3 are the check valves such as that shown at 26 in Fig. 4. There is one of these check valves to each cylinder A, B, C and D. These valves permit the passage of air out of the cylinders, but prevents the return of air to the cylinders. A pipe 27 having branches 27 a is arranged to convey the air forced from the cylinders to a common reservoir (not shown) where the air may be stored under pressure. A pipe 28 provided with a cut-off valve 29 (see Fig. 2) is arranged to communicate with the interior of the valve casing 3, by means of branch pipes 30 and 30 x respectively. The crank shaft 24 is connected to the pistons, as shown in Fig. 2. The pistons A and B are connected at 180° apart, the pistons C and D at 180° apart, and the pistons C and B at 90° apart.

From the foregoing description of the various parts of the device the operation thereof may be readily understood. When the device is to be used as an air compressor the valve 29 (see Fig. 2) is closed. The valves 7, 9, 7 x and 9 x are in a position to cover the ports a' , a^2 , b' , b^2 , c' , c^2 , and d' , d^2 respectively. We will show later how the valves are brought to this position. Power is applied to the crank shaft 24 in any suitable manner and the revolution of the crank shaft causes the reciprocation of the pistons A', B', C' and D'. Consider the piston A'. It is just at the end of its travel in the direction indicated by the arrow in Fig. 2. Air is being forced out of the cylinder A past the check valve 26 (see Fig. 4) and into the common pipe 27 leading to the reservoir (not shown). The piston B' is drawing air through the opening 25 y and past the check valve v in the inlet b . The piston C' is forcing air out into the common reservoir and the piston D' is drawing air through the inlet 25 x and past the valve v in the inlet opening d . The operation thus far described is that of an ordinary air pump or compressor. When the device

is running as an air pump, the small springs k and k^x hold the bell-crank levers 19 and 19 x in such a position as to raise the rods 21 and 21 x so that the highest part of the cams 23 and 23 x , i. e., the part 23 a shown in Fig. 3, will just graze the lower end of the rod. There will therefore be no movement of the piston rods 18 and 18 x (see Fig. 2) which are engaged by the bell-crank levers 19 and 19 x respectively, after each piston rod has been pushed inward to the position where all the ports a' , a^2 , b' , etc., are covered. Now when it is designed to run the device as a motor the valve 29 is opened to permit the air to enter from any source of compressed air (not shown). Consider now the conditions when the air enters the chamber 5 in Fig. 5 through the pipe 30, and that the low part 23 b of the cam 23 is up and the high part 23 a of cam 23 x is up. The area of the piston valve 7 is greater than the area of the piston valve 9 and hence the two valves will move to the right in Fig. 5, but since the cylinder 11 is rigidly secured to the valve stem it will also move to the right. Furthermore, air entering through the opening 16 and passing along the passage 15 will force the piston 17 to the end of the cylinder 11 and will therefore move the contact rod 18 outwardly. The rod 18 which is in contact with the bell-crank lever 19 will rotate the latter on its pivot so as to force the rod 21 downwardly into the path of the rotating cam 23. The movement of the piston valves 7 and 9 to the right in Fig. 5, will cause them to cover the ports a' and b' and to uncover the ports a^2 and b^2 . Compressed air will enter through the port a^2 and drive the piston A' in the direction shown by the arrow (Fig. 5). The piston B' is running in the direction shown by the arrow and the port b^2 will serve as an exhaust port to permit the air to pass through the space between the piston valves 9 and 9 x and out at the opening 25 y .

It will be understood that the valves 7 and 9 in Fig. 5 cover the ports a' and b' only when the cam rod 21 (see Fig. 2) is on the lower portion 23 b (see Fig. 3) of the cam 23. When, however, the surface 23 x , which is the higher surface of the cam, engages the rod 21 it will tend to rotate the bell-crank lever 19 so as to force the stem 18 inwardly. Now the space between the piston 17 and the head 12 of the cylinder is occupied by compressed air, and therefore as the rod 18 moves inwardly it will move the cylinder 11 and also the valves 7 and 9 against the pressure of the air, because the cam is positively operated. This occurs at the moment of the reversal of the pistons A' and B' so that when the piston A' is moving upwardly the port a^2 is closed and the port a' is opened. The exhaust air is therefore forced through

the port a' and through the chamber 4 at the outlet 25. When the valve 9 uncovers the port b' and covers the port b^2 , pressure will enter through the port b' and force the piston B' downwardly. Since the high surfaces on the cams 23 and 23 x are 180° apart it therefore follows that while the valves 7 and 9 are moved to the right by the pressure of the air coming in from the reservoir 5 through the pipe 30 the piston valve 7 x and 9 x are also moved to the right by the fact that the cam 23 x has moved the cam lever 19 x so as to positively force the stem 18 x inwardly and thereby moving the cylinder 10 11 x and the valves 7 x and 9 x as described. This condition is shown in Fig. 5, so that in Fig. 5 pressure is entering from the pipe 30 and passing through the ports c^2 , thus driving the piston C' downwardly. The piston 20 D' is forcing air out from the port d^2 and through the exit port 25 x . When air is admitted through the passages 15 or 15 x into the interior of the cylinders so as to provide a cushion, the compressed air between the 25 head of the cylinder and the small piston 17 or 17 x contained in these cylinders, the effect is to thrust the piston stems 18 or 18 x outwardly into the path of the vibrating bell-crank levers 19 and 19 x . This will permit the levers 19 and 19 x to move the valves 30 7, 9, 7 x and 9 x so as to uncover one port and to cover the other alternately. In other words, it will give a full throw to the valves. When, however, the valve 29 is closed, while 35 the motor is still running the pistons will keep on working as long as there is momentum in the fly wheel (not shown). Thus the pressure in the chambers 5 and 5 x will rapidly lower, the pressure will be relieved 40 from the interior of the cylinders 11 and 11 x and the pistons 17 and 17 x will be permitted to come in contact with the extension 14 of the valve stem, the travel of pistons 17 and 17 x in the cylinders 11 and 11 x respectively 45 being equal to half of the total valve travel.

Now when the bell-crank levers 19 and 19 x are forced inwardly by the cams the pistons 7, 9, 7 x and 9 x will be only moved half a stroke so as to bring them into the position 50 shown in Fig. 2. The effect is the same as if the rods 18 and 18 x had been suddenly shortened. The springs 10 and 10 x are of just sufficient length to force the piston valves outward from the center to a position 55 covering all ports, and the shortening of the stems 18 and 18 x (by air being removed from the cylinders 11 and 11 x) causes the cam action to force the piston valves in toward the center to position covering all the 60 ports. The springs k and k^x will cause the bell-crank levers 19 and 19 x to lift the rods 21 and 21 x , as described, so that when the device is used as a pump the sliding valves 65 will be out of commission entirely. There is therefore no wear on these sliding valves

while the device is being used as a pump. As the device is being used as a pump the greater part of the time it will be readily seen that there is very little wear indeed on these sliding valves. Furthermore by 70 means of springs k and k^x the rods 21 and 21 x are held up out of the path of the cams.

From the above description it will be seen that the opening or closing of the cock 29 virtually changes this device from a motor 75 to an air compressor or vice versa and that the mechanism described automatically adjusts itself so as to reduce the wear on the parts.

We claim:

1. In a combined air motor and compressor, a plurality of cylinders each provided with an inlet check valve and an outlet check valve, and an inlet port and an outlet port, a valve casing common to all 80 of said cylinders, slide valves in said valve casing for controlling the ports of each cylinder, and means for shifting said slide valves to alternately cover and uncover said inlet and said outlet ports when the device 85 is used as a motor, the shutting off of the motive fluid serving to permit the valve-actuating devices to move the valve so as to cover all of said ports.

2. In a combined air motor and compressor, a cylinder, a piston therein, said cylinder having an inlet check valve and an outlet check valve, and an inlet port and an exhaust port, a valve casing, a piston valve disposed within said valve casing 95 for controlling said ports, an auxiliary cylinder disposed within said valve casing, said cylinder having a rigid connection with said piston valve, an auxiliary piston within said auxiliary cylinder, a piston rod or stem 100 connected to the said auxiliary piston and arranged to project through said valve casing, means for supplying fluid pressure in the interior of said auxiliary cylinder, and movable means outside of said valve casing 105 for engaging the end of said auxiliary piston rod for moving the latter.

3. In a combined air motor and compressor, a crank shaft, a cam on said crank shaft, a cylinder, a piston within said cylinder arranged to be operated by said crank shaft, said cylinder having an inlet check valve and an outlet check valve, and an inlet port and an exhaust port, a valve casing, a piston valve disposed within said valve casing for controlling said ports, an auxiliary cylinder disposed within said valve casing, said cylinder having a rigid connection with said piston valve, an auxiliary piston within said auxiliary cylinder, 115 a piston rod or stem connected to the said auxiliary piston and arranged to project through said valve casing, means for supplying fluid pressure in the interior of said auxiliary cylinder, movable means outside of said auxiliary cylinder, 120

125

130

- 41
- of said valve casing for engaging the end of said auxiliary piston rod for moving the latter, said last named movable means comprising a bell-crank lever, one end of the 5 bell-crank lever being in the path of said auxiliary piston stem, and a cam rod pivotally connected with the other end of the bell-crank lever and arranged to be engaged by the cam on said crank shaft.
- 10 4. In a combined air motor and compressor, a cylinder, a piston therein, an inlet check valve and an outlet check valve for said cylinder, said cylinder also having an inlet port and an exhaust port, a valve 15 casing, a piston valve within said casing for controlling said ports, a reciprocating member disposed outside of said valve casing, a rod arranged to extend through the end of said valve casing in the path of said 20 reciprocating member for moving said piston valve, and means for varying the position of the rod with respect to the reciprocating member, thereby varying the length of stroke of the piston valve.
- 25 5. In a combined air motor and compressor, a main cylinder, a piston therein, said cylinder having an inlet port and an exhaust port, a valve casing, a piston valve disposed within said casing for controlling 30 said ports, said piston valve having a stem provided with a passage, an auxiliary cylinder disposed within said valve casing and having rigid connection with said piston valve, the interior of said auxiliary cylinder 35 having communication with said passage, a piston within said auxiliary cylinder having a stem arranged to extend through one end of said cylinder and outside the valve casing, a bell-crank lever arranged to engage 40 the end of the stem of said auxiliary piston, means for reciprocating said bell-crank lever, and means for admitting compressed air on one side of said piston valve, the passage of air into the interior of said 45 auxiliary cylinder serving to move said auxiliary piston thereby extending the stem of the latter toward the reciprocating member.
6. In a combined air motor and compressor, a main cylinder, a piston therein, said 50 cylinder having an inlet port and an exhaust port, a valve casing, a piston valve disposed within said casing for controlling said ports, said piston valve having a stem provided with a passage, an auxiliary cylinder disposed 55 within said valve casing and having rigid connections with said piston valve, the interior of said auxiliary cylinder having communication with said passage, a piston within said auxiliary cylinder having a 60 stem arranged to extend through one end of said cylinder and outside the valve casing, a bell-crank lever arranged to engage the end of the stem of said auxiliary piston, means for reciprocating said bell-crank lever, and means for admitting compressed air on one side of said piston valve, the passage of air into the interior of said auxiliary cylinder serving to move said auxiliary piston thereby extending the stem of the latter toward the reciprocating member, a second main cylinder having an inlet and an exhaust port, a piston valve for controlling the ports of said second main cylinder, said last-named piston valve being secured to the stem of said first-named piston valve, and its area being smaller than that of the first-named piston valve.
7. In a combined air motor and compressor, a main cylinder, a piston therein, said cylinder having an inlet port and an exhaust port, a valve casing, a piston valve disposed within said casing for controlling said ports, said piston valve having a stem provided with a passage, an auxiliary cylinder disposed within said valve casing and having rigid connections with said piston valve, the interior of said auxiliary cylinder having communication with said passage, a piston within said auxiliary cylinder having a stem arranged to extend through one end of said cylinder and outside the valve casing, a bell-crank lever arranged to engage the end of the stem of said auxiliary piston, means for reciprocating said bell-crank lever, and means for admitting compressed air on one side of said piston valve, the passage of air into the interior of said auxiliary cylinder serving to move said auxiliary piston thereby extending the stem of the latter toward the reciprocating member, a second main cylinder having an inlet and an exhaust port, a piston valve for controlling the ports of said second main cylinder, said last-named piston valve being secured to the stem of said first-named piston valve, and its area being smaller than that of the first-named piston valve, and a crank shaft for operating the pistons in both of said main cylinders, said crank shaft having crank arms extending in opposite directions, one of said crank arms being connected to the piston in one of said main cylinders and the other crank arm being connected to the piston in the other main cylinder.
